[57] CLAIM

The ornamental design for hand holdable housing for a
game, substantially as shown and described.

DESCRIPTION

FIG. 1 is an oblique view of the front, the top and the
right side of my new design for a hand holdable housing
for a game;

FIG. 2 is a side elevational view of the left side of the
design of FIG. 1;

FIG. 3 is a rear elevational view of the design of FIG.
1; and

FIG. 4 is a bottom plan view of the design of FIG. 1.
